Primary Examiner — Joseph Kukella(74) *Attorney, Agent, or Firm* — Lee & Hayes, P.C.(57) **CLAIM**

The ornamental design for a solar-charging mounting bracket for video doorbell, as shown and described.

DESCRIPTION

FIG. 1 is a front perspective view of a solar-charging mounting bracket for video doorbell;
FIG. 2 is a front elevational view thereof;
FIG. 3 is a rear elevational view thereof;
FIG. 4 is a right-side elevational view thereof;
FIG. 5 is a left-side elevational view thereof;
FIG. 6 is a top plan view thereof; and,
FIG. 7 is a bottom plan view thereof.

In the drawings, the broken lines depict features of the solar-charging mounting bracket for video doorbell that form no part of the claimed design.
